UNITED STATES PATENT OFFICE.

FAY F. FISHBACK AND EZRA STARK FISHBACK, OF EAST ORANGE, NEW JERSEY.

DESIGN FOR A BARBER'S CABINET.

48,061.

Specification for Design.

Patented Nov. 2, 1915.

Application filed July 1, 1915. Serial No. 37,597. Term of patent 7 years.

To all whom it may concern:

Be it known that we, FAY F. FISHBACK and EZRA S. FISHBACK, citizens of the United States, residing at East Orange, in the county of Essex and State of New Jersey, have invented a new, original, and ornamental Design for Barbers' Cabinets, of which the following is a specification, reference being had to the accompanying drawing, forming a part thereof.

The figure is a perspective view of a barber's cabinet, showing our new design.

We claim:

The ornamental design for a barber's cabinet, as shown.

FAY F. FISHBACK.

EZRA STARK FISHBACK.

Witnesses:

W. E. WALLACE,

FRED. D. CASTLE.
